UNITED STATES PATENT OFFICE.

FELIX GOTTLICHER, OF SAN FRANCISCO, CALIFORNIA.

DESIGN FOR AN ELECTRIC SWITCH PLATE.

Application filed March 3, 1926. Serial No. 16,756. Term of patent 14 years.

To all whom it may concern:

Be it known that I, FELIX GOTTLICHER, a citizen of the United States, residing at the city and county of San Francisco, State of California, have invented a new, original, and ornamental Design for an Electric Switch Plate, of which the following is a specification, reference being had to the ac-

companying drawings, forming part thereof. Fig. 1 is a front elevation showing my design.

Fig. 2 is a sectional elevation of the same.

I claim:

The ornamental design for an electric switch plate, substantially as shown.

FELIX GOTTLICHER.
